UNITED STATES PATENT OFFICE.

WILLIAM F. MASON McCARTY, OF BALTIMORE, MARYLAND.

PROCESS OF TREATING PETROLEUM-OILS.

1,274,912.

Specification of Letters Patent.

Patented Aug. 6, 1918.

Application filed August 17, 1916. Serial No. 115,513.

To all whom it may concern:

Be it known that I, WILLIAM F. M. McCARTY, a citizen of the United States, residing at Baltimore, in the State of Maryland, have invented certain new and useful Improvements in Processes of Treating Petroleum-Oils, of which the following is a specification.

This invention relates to a process of 10 treating crude petroleum or a petroleum oil or fraction having a higher boiling point than gasolene, to produce an increased yield of gasolene and more or less similar volatile hydrocarbons adapted for use as motor fuels, 15 and, in its preferred embodiment, my improved process is designed to effect the production from petroleum material and particularly crude petroleum, of not only gasolene like bodies adapted for use as motor 20 fuels but aromatic hydrocarbons and particularly benzin and toluene adapted for use in the manufacture of explosives.

In the practice of my process, in its preferred embodiment, petroleum oil, preferably crude oil, is heated in the presence of an aluminum salt such as the chlorid or sulfate of aluminum and water. I prefer to add to the petroleum in a suitable receptacle, five per cent. of its weight of water containing five per cent. by weight of aluminum sulfate or alum. The receptacle is then hermetically sealed and superheated steam preferably under a pressure of about 150 pounds per square inch is introduced for a period of 30 preferably from fifteen minutes to thirty minutes. As a result of this action a mixture is produced. The steam is then shut off and the water contained in the oil is allowed to settle and is then drawn off. It is obvious 35 that the alum serves as a refining agent, to drag down tarry matter and other impurities in the oil, the same being removed from the oil when the water is withdrawn, as above stated. After the withdrawal of 40 the water, steam is again introduced into the treated petroleum material, preferably under a pressure of 150 pounds per square inch until the temperature of the oil is raised to preferably from 250 to 300° C. The treated 45 oil is then caused to pass through a super-heating coil maintained at a temperature of preferably 400° C. It is then intimately mixed with hydrogen preferably in the proportions of one part by weight of hydrogen to 500 parts by weight of the vaporized oil. The proportion of hydrogen used should be

sufficient to saturate the unsaturated molecules and an excess of hydrogen should be used. The mixture is then passed into and through a cracking tube or retort which is 60 preferably maintained at a constant temperature of 600° C., and in this cracking tube or retort the mixture is subjected to the action of catalytic metal, preferably nickel. The pressure in the cracking tube 65 or retort is preferably maintained at about fifty pounds per square inch. Under these conditions the petroleum material under treatment is decomposed with the production of the maximum production of gasolene 70 like materials, benzin and toluene and a minimum production of gas, carbon and tarry matters.

The products of decomposition are passed from the cracking tube or retort into a suitable condenser where the condensable hydrocarbons are separated and the gaseous portion of the decomposition products is collected in a suitable gas holder.

I have found that improved results over 80 those resulting from the processes now commonly in use may be obtained without the preliminary treatment of the petroleum material with an aluminum salt but improved results are obtained where the preliminary 85 treatment with the aluminum salt is carried out.

I have also found that particularly good results are obtained by using hydrogen in a nascent state, that is to say, immediately 90 upon its production.

In the accompanying drawings forming a part of this specification and in which like numerals are employed to designate like parts throughout the same,

Fig. 1 is a side elevation of apparatus preferably employed in the practice of my process,

Fig. 2 is a horizontal sectional view through a retort, taken on line 2—2 of 100 Fig. 3,

Fig. 3 is a central vertical longitudinal sectional view through the retort,

Fig. 4 is a similar view through the lower end of the retort, the upper portion thereof 105 being broken away,

Fig. 5 is a horizontal sectional view taken on line 5—5 of Fig. 4,

Fig. 6 is a similar view taken on line 6—6 of Fig. 4,

Fig. 7 is an enlarged fragmentary sectional view through the cracking or heating

tube, showing agitating means arranged therein, and,

Fig. 8 is a horizontal sectional view taken on line 8—8 of Fig. 7.

- 5 In the drawings, the numeral 15 designates a closed receptacle, to the upper end of which is connected an oil supply pipe 16. This pipe 16 is equipped with a cut off valve 17. A water supply pipe 18 is also connected 10 with the upper end of the receptacle 15 and has a cut off valve 19. Leading into the upper end of the receptacle 15 and extending therein to terminate near and spaced from its bottom, is a steam supply pipe 20, having 15 a cut off valve 21. The receptacle 15 is provided at its bottom with a water draw-off or drain pipe 22, having a cut off valve 23. Connected with the receptacle 15, preferably 20 near its lower end, is a take off pipe 24, leading into a super-heater 25, and having connection with the lower end of a coil 26 thereof. The upper end of the coil 26 is connected with a pipe 27, for a purpose to be described.
- 25 The pipe 27 is provided with a plurality of branches 28, leading into retorts 29. As more clearly shown in Fig. 3, each branch 28 is equipped with a cut-off valve 30. Each retort 29 comprises an outer casing or body 30 portion 31, preferably lined with suitable heat resisting material. The numeral 32 designates a heat generating device, such as oil or gas burners, adapted to provide flames which project inwardly within the 35 casing 31, as is obvious. The fuel is supplied to the burners 32 through a pipe 33 or the like.

Extending longitudinally and centrally within the casing 31 is an inclosing conduit 33', which is preferably square in cross-section and formed of heat resisting material. This conduit is held in place by spacing elements 34, as shown. The upper end of the inclosing conduit 33' is open and in free 40 communication with the interior of the retort casing 31, while its lower end is closed and connected with an outlet 35, in turn connected with a stack 36. Extending longitudinally within the conduit 33' is a cracking tube 37, the upper end of which is provided with a cap 38.

The numeral 39 designates a sleeve, provided at its upper end with a flange 40, arranged beneath the cap 38 and upon the 55 upper flanged end of the tube 37. These flanges are secured together by bolts 41 or the like. The lower end of the tube 39 is provided with a casting or nozzle 42, having an outlet opening 43, which flares downwardly, for spraying the oil. Leading into the outlet opening 43 is a vapor or hydrogen supply pipe 44, having a cut off valve 45. The vaporized oil and hydrogen, which become intimately mixed in the opening of the 60 nozzle 42, spray downwardly and impinge

against a curved stationary baffle plate 46, which deflects the gaseous mixture laterally into the upper end of the cracking tube 37.

Extending longitudinally within the cracking tube 37 is a reciprocatory and rotatable 70 rod 47, to which are secured agitator or scraping elements or paddles 48, which are formed partly or wholly of catalytic material, such as nickel, while other catalytic material may be employed. The rod 47 is 75 journaled through a suitable bearing 49, and the lower end of this rod carries annular flanges or disks 50, rigidly secured thereto. Arranged between the flanges 50 is a cam 51, carried by a shaft 52. The shaft 52 is driven 80 by a bevel gear 53, (see Fig. 4) engaging a bevel gear 54, carried by a shaft 55, which receives its rotation from any suitable source of power. Splined upon the shaft 47 is a sleeve 56, adapted to rotate with the shaft, 85 but does not partake of longitudinal movement and permits of the free reciprocatory movement of the shaft 47. The sleeve 56 has a worm gear 57, rigidly attached thereto, as clearly shown in Figs. 4 and 6, and this worm wheel is driven by a worm 58, carried by the shaft 59. The shaft 59 is rotated by any suitable means and at a desired speed.

Connected with the lower end of the cracking tube 37, as more clearly shown in 95 Figs. 4 and 5, is an enlarged collecting chamber 60, in the bottom of which is mounted to rotate a scraper 61. This scraper is carried by the sleeve 56 and rotates therewith. The agitators or scrapers 48, by their 100 combined rotatable and reciprocatory movements, serve to remove the carbon deposits from the interior of the cracking tube 37, and these deposits, together with more or less uncracked oil, gravitate into the chamber 105 60 and are subjected to the action of the rotating agitator 61. The carbon deposits, with more or less oil, discharge from the chamber 60, through a conduit 62, into a holding tank 63. The carbon with the oil, 110 which passes into the tank 63, are allowed to settle and the oil may be withdrawn through a pipe 64, having a cut off valve 65', while the carbon gravitates into a trap 65, having a door 66, and may be removed therefrom. 115

As more clearly shown in Fig. 3, each chamber 60 has a vapor or gas outlet pipe 67, leading into the upper portion thereof, with a baffle 67' disposed in advance of the same. The products of distillation are withdrawn 120 through the pipe 67 and the baffle 67' prevents the carbon or solid deposits from passing over with the products of distillation. Leading into each chamber 60, is an oil draw-off pipe 68, the intake end of which is 125 arranged near and above the agitator 61. The pipe 68 has a cut off valve 69. The un-cracked oil and carbon, in the chamber 60, tend to separate to a certain extent, and the oil on top is withdrawn through the pipe 130

68. The oil in the pipe 68 may be pumped back into the shell 15 and again treated by passing through the apparatus.

The take off pipes 67 for the gaseous products of distillation, discharge into a common pipe 70, which conduct the gases to traps 71, for depriving the same of water. The gases are then passed by the pipe 70 into a coil 72 of a condenser. The lower end of the coil 72 discharges into a trap 74, wherein the condensed gases are collected and may be withdrawn through a pipe 75. The gases which do not condense discharge from the trap 74 into a pipe 75, which leads into a gas holding tank 76.

In the practice of my process in connection with the apparatus herewith shown and described, the oil, such as crude petroleum oil, is introduced into the closed receptacle 15 through the pipe 16, and the valve 17 is closed. The valve 19 is opened and water, in the proportions of five per cent. by weight of water with respect to the weight of oil, such water containing five per cent. by weight of an aluminum salt, such as alum, aluminum, chlorid, or aluminum sulfate, is fed through the pipe 18 into the closed receptacle 15, in the presence of the oil. The valve 19 is closed and the valve 23 is also closed. The steam valve 21 is now opened, and super-heated steam, preferably under a pressure of about 150 pounds to the square inch is introduced into the receptacle 15 for a period of preferably from 15 minutes to 30 minutes. As a result of this action, the oil and water are thoroughly agitated in the presence of heat and pressure and a mixture is produced. The formation of desired decomposition products during the cracking operation is materially aided by the prior treatment with steam and alum or other aluminum compounds as hereinbefore described. The steam valve 21 is now closed and the contents of the receptacle 15 is allowed to settle so that the water may be withdrawn from the oil by opening the valve 23. It is obvious that the alum in the water serves as a refining agent to drag down the tarry matter and other impurities, which are removed from the oil, when the water is withdrawn, as above stated. This valve 23 is again closed, and the steam valve 21 is again opened, so that steam is supplied into the receptacle 15 in the presence of the oil, such steam being preferably under a pressure of 150 pounds per square inch, until the temperature of the oil is raised to preferably 250 to 300° C. The valve 24 in the pipe 24 is now opened, and the pressure in the receptacle 15 forces the oil into the super-heating coil 26, which is preferably maintained at a temperature of 400° C. In the super-heating coil, the oil is vaporized and discharges through the pipe 27. This vaporized oil then passes to the several re-

torts, for treatment therein, and such treatment in only one retort will be given, since the operation of the several retorts are identical. By turning to Fig. 3 of the drawings, it will be seen that the gasified oil discharges through the pipe 28 into the tube 39, and then passes into the spraying nozzle 42. In this spraying nozzle the gasified oil is intimately mixed with incoming hydrogen gas supplied through the pipe 44, and this mixture of the gaseous oil and hydrogen gas impinges upon the baffle plate 46. The hydrogen gas is preferably supplied to the gaseous oil in the proportions of one part by weight of hydrogen to five hundred parts by weight of the gaseous oil. The proportions of hydrogen should be sufficient to saturate the unsaturated molecules in the gaseous emulsion and an excess of hydrogen should be used. The mixture of the gaseous oil and hydrogen discharge into the cracking tube 37, which is preferably maintained at a constant temperature of 600° C. While being subjected to the action of heat within the cracking tube, this mixture is also subjected to the action of a catalytic agent, preferably in the form of the nickel agitators 48. The pressure in the cracking tube is preferably maintained at about 50 pounds to the square inch. While the gaseous mixture is undergoing treatment in the cracking tube, as above indicated, the rod 47 is constantly reciprocated and rotated at suitable speeds. The agitators 48 keep the gaseous mixture in a suitable state of agitation, whereby they are maintained at the uniform temperature of the tube 37, to wit, 600° C. The agitators 48, by reciprocating and rotating in close proximity to the inner wall of the tube 37, serve to remove therefrom the carbon deposits which gravitate into the chamber 61, with more or less uncracked oil, and the same are removed therefrom, as hereinabove explained. Under the above stated conditions of treatment, the oil or the petroleum material, is decomposed with the production of the maximum yield of gasoline like materials, benzine and toluene and the minimum yield of gas, carbon, and tarry matters.

These gaseous products of distillation are conducted through pipe 70 and pass through the traps 71, to remove the water therefrom. The gaseous products then pass into the coil 72 of the condenser, wherein a part is condensed; the hydrocarbons then pass to the trap 74 and are separated from the gaseous hydrocarbons. The condensed hydrocarbons are collected within the trap 74 and may be removed therefrom to the pipe 75, while the gaseous hydrocarbons pass through the pipe 75 into the gas holding tank 76.

The apparatus shown and described in this application is not claimed herein as the same is disclosed and claimed in my co-

pending application for apparatus for treating petroleum oils, filed August 17th, 1916, Serial No. 115,514.

It is to be understood that the form of my invention herewith shown and described is to be taken as a preferred example of the same, and that various changes may be resorted to in the order of the steps of the process, the temperatures employed in the treatment of the material, and the general procedure of the process, without departing from the spirit of my invention or the scope of the subjoined claims.

Having thus described my invention, I claim:

1. The herein described process of treating petroleum oils, fractions and the like having a higher boiling point than gasoline, which consists in subjecting the oil to the action of superheated steam in a closed container at substantially 150 pounds pressure to the square inch in the presence of a water-soluble aluminum compound and water, allowing the mass to settle, withdrawing the water and the material held in solution or suspension therein from the oil, subjecting the oil thus treated to the action of heat at substantially 400° C. for vaporizing the same, subjecting the vaporized oil to a tempera-

ture of substantially 600° C. in the presence 30 of hydrogen and a catalytic agent for decomposing the same, and condensing the condensable portion of the decomposition products.

2. The herein described process of treat- 35 ing petroleum oils, fractions and the like having a higher boiling point than gasoline, which consists in subjecting the oil to the action of heat from substantially 250 to 300° C., in the presence of water and a wa- 40 ter soluble aluminum compound, allowing the mass to settle, withdrawing the water and the material held in solution or suspen- 45 sion therein from the oil, subjecting the oil thus treated to the action of heat to vaporize the same, subjecting the vaporized oil to a temperature of approximately 600° C., and a pressure of approximately 50 pounds to the square inch, in the presence of hydrogen 50 and a catalytic agent to decompose the va- porized oil, and condensing the condensable portion of the decomposition products.

In testimony whereof I affix my signature in presence of two witnesses.

WILLIAM F. MASON McCARTY.
